SPRING CLASPS

Ulrich C. Dunaway, Clayton, Mo.

Application December 23, 1955, Serial No. 555,103

3 Claims. (Cl. 24—254)

The present invention relates to fastening devices generally, and has particular reference to improvements in spring clasps.

The device of my invention has particular application and usefulness as means for attaching signs or warning flags to electrical apparatus undergoing renovation or repairs to indicate zones of danger to be avoided by the workman. The clasp of my invention greatly facilitates the work of installing and removing the signs by enabling those operations to be performed with the use of a long-handled tool, thereby eliminating much of the climbing otherwise necessary to post the danger spots, and to reduce the hazard involved with those operations.

The object of the present invention is to provide an improved fastening device or clasp of the character and for the purpose described, which will operate to connect itself to an appropriate object by the simple maneuver of bring the device into contact therewith, so that manipulation of the device to make a remote connection may be made with the use of a long-handled tool.

Another object is to provide a clasp of this character which securely affixes itself to the element or part to which it is applied, yet which is easy to remove, also with the use of a pole.

The invention resides in the construction and combination of the parts that make up my improved clasp and which render it a superior, effective and highly practical device. The foregoing and other objects and advantages of the clasp hereof will appear from the following specification, reference being made therein to the drawing, in which:

Fig. 1 is a perspective view showing the clasp hereof in use for fastening a warning device to part of an electrical installation;

Fig. 2 is a side elevational view showing the clasp mounted on an applicator tool and with jaws of the clasp in open position;

Fig. 3 is a top or end view of the assembly illustrated in Fig. 2, and

Fig. 4 shows the clasp with the jaws in closed position.

Referring now by characters of reference to the drawing, the clasp, indicated generally at 4, Fig. 1, comprises a pair of members designated 5 and 6 formed in the present example of light weight metal such as aluminum. These members are pivotally connected together by a pin 7 and their inner margins are shaped to provide concavely arcuate jaw faces 8 and 9 which are adapted to coact to embrace an appropriate object, such as the electrical conductor shown. A spring 10 is connected to the jaw members and acts thereon to force them together, or to closed position, as shown in Fig. 4. The jaws are initially held in open position (Fig. 2) against the closing force of said spring by a detent 11 which has one end pivoted by a pin 12 to jaw 6, and is arranged to have its opposite end releasably engage a keeper bar 13. An intermediate portion of detent 11 protrudes into the space environed by the open jaw

2

faces 8 and 9, where, like the trigger of a spring trap, it is susceptible of being tripped by contact with an object entering the said space, thus to release the jaws and allow them to spring to a closed position about the object.

Now describing the device in greater detail, the jaw member 5 is of bifurcated construction, comprising flat, generally claw-shaped side portions 5a and 5b which are spaced apart to provide an opening between them to receive the other jaw member 6. Side portions 5a and 5b are joined together at their back edges by a transverse web 14 which has a slot 15 therein. This slot extends upwardly from an opening at the lower edge of the web 14 and is adapted to receive a side projecting fin 16 formed on the head of a long-handled applicator tool 17. As best appears from Figs. 2 and 3, the applicator tool head is adapted to interfit with the slotted portion of the member in a manner to afford a firm mounting for the clasp on the applicator tool which, after the clasp has been installed, may be downwardly disengaged therefrom.

The pivot pin 7 extends transversely between the side portions 5a and 5b near the lower ends of the arcuate jaw faces 9 of those portions and passes through the hub part 18 of jaw member 6. Member 6 is provided with an integral ring 19, extending downwardly from the hub part 18. The ring 19 affords a means for attaching the warning flag or sign 21 to the device as shown in Fig. 1, and is used for removing the device from the object to which it is attached. Thus, the ring or eye portion 19 is of sufficient size to enable it to be easily hooked by a projecting finger such as 22 on the end of the applicator tool 17. Removal of the device may then be accomplished by pulling downwardly on the ring portion 19, causing jaw 5 to be forced open by the camming action thereon of the supporting object.

At its upper end jaw member 6 curves backwardly in the provision of a hook 23 which serves in lieu of the described jaw means for attaching the device to certain types of electrical apparatus, such as to a high tension disconnect switch. The blades of those switches are customarily provided with ring portions and such portions afford a convenient means for receiving the hanger hook 23 of the flag holding device hereof.

45 The torsion spring 10 acts on the jaw members 5 and 6 to force them toward closed position which is shown in Fig. 4, and the same spring acts on the detent member 11 to move it toward its normal latching position, which is shown in Fig. 2. Spring 10 has paired arm portions 10a and 10b extending at opposite sides of jaw member 6, and each thereof includes a loop portion that encircles the pivot pin 7, and a forward end having a hooked extremity that bears against the transverse keeper bar 13. The opposite end portions of spring arms join 55 the transverse yoke 26 of the spring which yoke crosses the back edge of member 6, and bears against a rearwardly protruding portion 27 of detent 11. Detent 11 is mounted in a slotted passage that extends transversely through the central part of jaw member 6 and is defined 60 between end surface indicated by dotted lines 28 and 29, Fig. 4. The said detent, pivoted to jaw 6 by pin 12, curves outwardly so as to protrude laterally into the opening formed by the open jaw members (Fig. 2). The end of the detent is provided with a recess 30 forming a shoulder to bear against the keeper bar 13 and thereby hold the jaw member open. It will be understood that the detent is pressed by the yoke portion 26 of spring 25 to a position wherein it is readily engageable by the keeper bar 13 when the jaw members are "cocked" to 65 open position. When in such position the detent is adapted to be tripped by contact with the object to which the clasp is to be applied.

The operation of the clasp and method of applying the same will be understood from the foregoing description, but for purposes of completeness these may be stated briefly as follows. The clasp assembly 4, with the sign, warning flag or other object 21 (Fig. 1) suspended from the ring portion 19 is mounted on the lineman's stick 17 in the manner shown in Fig. 2. The jaw member 6 is then cocked to open position, causing a latching of the detent 11 with the keeper bar 13 and projecting the bowed central portion of the detent into 10 prominence at the base of the throat defined by the jaw members 5 and 6. With the use of the stick 17 the assembly is manipulated to bring the detent into forceful contact with the object selected to carry the sign, displacing the detent and allowing the jaw members to embrace the said object. The stick is then lowered to disengage its key portion 16 from the key slot formed in the web 14.

Removal of the clasp is accomplished by linking the side projecting part 22 of the tool 17 with the ring 19 and drawing downwardly thereon. Jaw 5 will pivot open and the smooth jaw face 9 will allow the jaw to slide free of the supporting object.

Having thus described my invention, I claim:

1. In a clasp device of the character described, a pair of members having curved, coacting jaw portions, pivot means interconnecting said members, a detent keeper on one of said members, a detent pivoted to the other member adapted releasably to engage said keeper to hold said jaw portions in open position, a spring encircling the pivot means and acting on said same members to force their jaw portions toward closed position, said spring also engaging said detent and acting to hold said detent in latched relation with the detent keeper on the said one member, said detent having an intermediate trigger portion between its pivot connection to one jaw portion and its keeper connection to the other jaw portion extending into the space between said curved jaw portions.

2. A clasp assembly for connecting an article to a remote object comprising coacting, pivotally connected members having opposed, concavely arcuate jaw faces, one of said members having opposed, relatively spaced side portions, the other member being movable in a 45 plane between and parallel to the side portions of the first member, a spring acting on said members to bring

said jaw faces toward each other, a detent pivotally mounted on one of the members and adapted releasably to engage the other member to hold said members in open jaw position against the acting of said spring, the same spring engaging said detent and acting to hold the same in latched relation with the said other member, said detent having a trigger portion between its pivot connection to one jaw portion and its latch connection to the other jaw portion extending into the space environed by said concave jaw faces, and means on one of said members for detachably connecting the assembly to an applicator pole.

3. A clasp device of the character described, comprising a first jaw member having spaced parallel side portions, a transverse web interconnecting said side portions at one end of said jaw member, a pivot pin extending transversely between said side portions at an opposite end of said jaw member, said web having a mounting slot entering from a lower edge thereof, adapted to coact with an applicator tool, a second jaw member pivoted to said pivot pin, said jaw members having opposed, arcuately concave jaw faces extending in a generally upwardly direction from the pivot pin, said second jaw member having an annular portion extending in a direction downwardly from said pin, a detent bar pivotally mounted on said second jaw member, a keeper on the first said jaw member adapted to be releasably engaged by said detent bar to hold said jaw members in open position, said detent bar protruding laterally into the space environed by the open jaw members, a tension spring having end portions acting on said jaw members in a direction tending to close the same, said spring also engaging said detent bar and acting to hold the same in latched relation with the first said jaw member.
